US0D1008153S

(12) **United States Design Patent** (10) **Patent No.:** **US D1,008,153 S**
(45) **Date of Patent:** **** Dec. 19, 2023**

(54) **MOUNTING FLANGE**

- (71) Applicants: **Daniel Ray Enyeart**, Gladstone, OR (US); **Evan Waymire**, Oregon City, OR (US)
- (72) Inventors: **Daniel Ray Enyeart**, Gladstone, OR (US); **Evan Waymire**, Oregon City, OR (US)

(**) Term: **15 Years**

(21) Appl. No.: **29/825,447**

(22) Filed: **Feb. 1, 2022**

Related U.S. Application Data

(63) Continuation-in-part of application No. 16/417,143, filed on May 20, 2019, now Pat. No. 11,548,375, which is a continuation-in-part of application No. 29/626,889, filed on Nov. 21, 2017, now Pat. No. Des. 886,958.

(57) **CLAIM**

The ornamental design for a mounting flange, as shown and described.

DESCRIPTION

FIG. 1 is an isometric view of a mounting flange showing our new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof;

FIG. 7 is rear elevation view thereof;

FIG. 8 is a cross-sectional view taken along line 8-8 in FIG. 2; and,

FIG. 9 is a cross-sectional view taken along line 9-9 in FIG. 2.

The dash lines in the drawings illustrate portions of the mounting flange that form no part of the claimed design.

1 Claim, 6 Drawing Sheets
